UNITED STATES PATENT OFFICE.

EMMET C. STANDIFORD AND JOHN T. TODD, OF CHRISMAN, ILLINOIS.

FASTENING FOR NECKTIES.

SPECIFICATION forming part of Letters Patent No. 248,228, dated October 11, 1881.

Application filed August 24, 1881. (No model.)

To all whom it may concern:

Be it known that we, EMMET CLARKSON STANDIFORD and JOHN THOMAS TODD, of Chrisman, in the county of Edgar and State 5 of Illinois, have invented a new and useful Improvement in Fastenings for Neckties; and we do hereby declare that the following is a full, clear, and exact description of the same, reference being had to the accompanying drawings, forming part of this specification, in which—

Figure 1 is a perspective view of the back face of our improved necktie and fastening. Figs. 2 and 3 are detail views.

Our invention relates to improvements in fastenings for neckties; and it consists in the peculiar construction and arrangement of the parts, as hereinafter more fully set forth.

In the accompanying drawings, *a* represents 20 the bow, and *b* the strap of a necktie, secured to the bow in the usual manner.

c represents a piece of elastic material inserted transversely across the strap to allow it to be adjusted to different-sized necks, and 25 *d* represents a hole in the outer end of the strap *b*, adapted to pass over the outer head of the collar-button.

h represents a clasp composed of the two plates or leaves *k l*, having a longitudinal edge 30 of one plate or leaf, *k*, hinged to a longitudinal edge of the other plate or leaf, *l*, and the outer leaf, *k*, being also provided with a spring, *s*, cut out of the plate or leaf *k*, the free end of which spring bears upon the edge of the plate 35 *l*, as seen in Fig. 2, so as to form a clasp having a spring-hinge. The outer leaf, *k*, is secured to the back face of the bow *a* over the inner end of the strap *b*, and the inner leaf, *l*, is provided with a longitudinal slot, *m*.

Our fastening device for a necktie is designed 40 to be employed in conjunction with any collar-button having a hinged or detachable outer

head, though we prefer to use the fastening with a collar-button having a hinged outer head.

In practice the collar-button is inserted in the button-holes of the shirt and collar with the hinged or detachable head outward. The hinged head is then turned downward, so as to lie in the plane of the shank of the collar-button, and inserted in the central slot, *m*, of the leaf *l* of the spring-clasp *h*, and the strap *b* of the tie is passed around the neck of the wearer, and the hole *d* in the outer end of the strap *b* is passed over the outer head of the 50 collar-button, in line with its shank. The outer head of the collar-button is then turned so that the heads of the collar-button are parallel with each other, and the spring-clasp closed.

By this construction the shirt, collar, and 60 necktie are securely fastened together, and there is no liability of the necktie slipping on the collar. The construction also is extremely simple and cheap, and can readily be applied.

We claim as our invention—

1. The necktie-fastening herein described, 65 consisting of the clasp *h*, having its leaves *k l* connected by a spring-hinge, and its leaf *l* provided with a slot, *m*, said clasp being adapted to be secured to the back face of the bow of a 70 necktie, substantially as described, and for the purpose set forth.

2. The necktie herein described, consisting 75 of the bow *a*, strap *b*, having hole *d* in its outer end, and elastic piece *c*, and spring-hinge *h*, secured to the inner face of the bow, and provided with a slot, *m*, in its inner leaf, *l*, substantially as described, and for the purpose set forth.

E. C. STANDIFORD.
JOHN T. TODD.
